UNITED STATES PATENT OFFICE.

MORRIS LOWY, OF NEW YORK, N. Y.

CORNER FASTENING FOR BEDSTEADS.

Application filed January 25, 1922. Serial No. 531,616.

To all whom it may concern:

Be it known that I, MORRIS LOWY, a citizen of the United States, and resident of the city of New York, in the county of 5 Kings and State of New York, have invented certain new and useful Improvements in Corner Fastenings for Bedsteads, of which the following is a specification.

The present invention relates to improvements in corner-fastenings for bedsteads, and has for its main object to provide a simple, efficient and durable device of this type which is capable of being conveniently struck up from sheet metal.

Another object of the invention is to produce a corner-fastening of the type mentioned, which permits of a convenient assembling of the bed and of a taking down of the same by inexperienced operators with 15 but little time and energy and without the aid of tools.

A further object of the invention is to so construct the corner-fastening that the bed-bottom supporting member may be clamped 20 thereto or released therefrom by an element that forms part of the corner-fastening, there being thus no chance of losing or misplacing the clamping member.

A still further object of the invention is 25 to so construct the corner-fastening that the bed-bottom supporting angle bar may be reversibly secured thereto, so as to adapt it to ordinary spring mattresses and also to box springs.

With these and other objects in view, which will more fully appear as the nature 30 of the invention is better understood, the same consists in the combination, arrangement and construction of parts hereinafter 35 described, pointed out in the appended claims and illustrated in the accompanying drawings, it being understood that many changes may be made in the size and proportion of the several parts and details of 40 construction within the scope of the appended claims, without departing from the spirit or sacrificing any of the advantages of 45 the invention.

Two of the many possible embodiments of 50 the invention are illustrated in the accompanying drawings, in which:—

Figure 1 is a side elevation of a corner-fastening, constructed in accordance with the present invention, in position upon the 55 corner-post of a bedstead, the bed-bottom supporting angle bar being shown positioned

to receive an ordinary spring mattress; Fig. 2 is a section taken on line 2—2 of Fig. 1; Fig. 3 is a section taken on line 3—3 of Fig. 1; Fig. 4 is a view similar to the one shown 60 in Fig. 1, showing the bed-bottom supporting angle bar positioned to receive a box spring; Fig. 5 is a view similar to the one shown in Fig. 1 of a modification of the invention; Fig. 6 is a section taken on line 65 6—6 of Fig. 5; Fig. 7 is a section taken on line 7—7 of Fig. 5; Fig. 8 is a view similar to the one shown in Fig. 4 of the said modification; and Fig. 9 is a perspective view of one of the ends of the angle bar employed in 70 the construction shown in Figs. 5 to 8, inclusive.

Referring now first to Figs. 1 to 4, inclusive, of the drawings, the numeral 10 indicates a portion of a rectangular corner-post 75 of a bedstead, to which the corner-fastening is to be attached. The corner-fastening includes a bracket-like hollow rectangular shell 11, preferably, made of one integral piece, for instance by stamping operations. 80 This shell includes a top wall 12, an inner side wall 13 and an outer side wall 14, from which extends inwards toward the wall 13 a bottom 15. From the said bottom projects downwards a vertically extending lug 85 16 that is spaced from the side wall 13 in parallel relation to the latter. The elements of the shell so far described extend longitudinally of the bedstead, that is to say at right angles to the longitudinal axis of the 90 corner-post 10 and serve to receive, in a manner hereinafter to be described, the bed-bottom supporting side rail 17, which is made in the form of an angle bar. The shell includes furthermore end members 18, one 95 of which engages the corner-post, while the other abuts against the first-mentioned end member. Screw bolts 18', passing through the said end members into the corner-post, serve to attach the shell to the said 100 post. The distance between the side walls 13 and 14 corresponds to that between the top wall 12 and bottom 15, so that the angle bar may be inserted into the shell in two positions. In one of these positions, shown 105 in Figs. 1 to 3, inclusive, the flange 19 of the angle bar constitutes the horizontal flange, the other flange, denoted by the numeral 20, being disposed vertically and below the flange 19. When so inserted, the 110 flange 19 abuts against the inner face of the top wall of the shell and the flange 20

- against the inner face of the outer side wall 14 thereof. In the other position, shown in Fig. 4 of the drawings, the flange 19 forms the vertical flange of the angle bar and the flange 20 the horizontal flange. In this last-named position, the flange 19 abuts against the inner face of the outer side wall 14 of the shell and the flange 20 rests upon the bottom 15 of the same.
- 10 For clamping the side rail to the shell, there is a lever 21 pivoted at 22 to the shell 11, the pivot being in the form of a screw bolt, that extends through the inner side wall 13 and through the lug 16. This lever 15 is provided within the shell with a cam 23, having an upper cam face 24 and a lower cam face 25. The upper cam face is adapted to co-operate with the top wall 12 and the lower cam face with the bottom 15 of the 20 shell. The lever is furthermore provided with a side cam face 26, adapted to coact with a lug 27, formed on the inner face of the inner side wall 13. The lever extends a considerable distance below the shell 11, so 25 that it may be manually actuated. On the lever is formed a projection 28, which abuts against the inner side wall 13 of the shell, when the said lever is shifted from the position shown in full lines in Fig. 1 of the 30 drawings into the position shown in dotted lines in said figure. The said inner side wall, in co-operation with the said projection, limits thus the movement of the lever 21 in one direction.
- 35 The flange 20 of the angle bar is partly cut off adjacent its end, as shown at 29, there being an oblong piece removed adjacent the free edge of the flange 20, the length of which corresponds substantially to that of 40 the shell, while its width is somewhat greater than the thickness of the lever 21. This cut out portion is provided to permit the angle bar to be inserted into the shell with its flange 20 resting upon its bottom 15.
- 45 The two shells 11 on the corner-posts, forming an end member of the bedstead, may be connected in any suitable manner, for instance by an angle iron 30, which is fastened by screws 31, or otherwise, to lugs 50 32, the latter being, preferably, made integral with the two shells.
- 55 The operation of the corner-fastening is as follows: If the bedstead is to be provided with an ordinary spring mattress, the angle bars 17 are inserted into the shells in the manner indicated in Figs. 1 to 3, inclusive, of the drawings, in which the flanges 19 of the said bars are disposed horizontally in contact with the top walls 12 of the shells.
- 60 In order to permit of such insertion, obviously the cam lever 21 must be shifted from the position shown in full lines in Fig. 1 of the drawings into the position shown in dotted lines in the said figure, so as to bring 65 its cam face 24 to a distance from the top

wall of the shell sufficient to permit of convenient insertion of the angle bar. After the angle bar has been put into place, the lever is shifted into the position shown in full lines in Fig. 1 of the drawings, whereby 70 its cam face 24 binds the horizontal flange 19 against the top wall of the shell. Simultaneously therewith, the side cam face 26 of the lever rides up the lug 27 on the inner side wall 13 of the shell, whereby the cam 75 lever is forced toward the side wall 14, clamping the vertical flange 20 against the said side wall. The angle bar may be conveniently disengaged from the shell by moving the lever 21 into the position shown in dotted lines in Fig. 1 of the drawings.

If it is desired to use a box spring on the bedstead, the angle bar must be reversed, that is to say it must be brought into the position shown in Fig. 4 of the drawings, in 85 which its flange 19 extends vertically, it being in abutment with the outer side wall 14 of the shell, the flange 20 resting on the bottom 15. The lever is then forced into clamping position, whereby its lower cam face 25 90 binds the flange 20 against the bottom 15, its flange 19 being clamped against the outer side wall 14 in the manner above described.

The modification illustrated in Figs. 5 to 9, inclusive, of the drawings, differs from 95 the one above described only in that its shell 11' is made narrower. The angle bar used in connection with this shell has both of its flanges cut off adjacent its ends, as shown in Fig. 9 of the drawings, oblong portions 29' 100 and 29'' being removed, to permit of an insertion of the said angle bar into the shell with the horizontal flange uppermost or lowermost, as desired. Otherwise the construction and operation of the elements are 105 the same as of those described in connection with Figs. 1 to 4, inclusive, of the drawings.

It is obvious that, while herein the shell has been described as made of one integral piece by stamping operations, the same may 110 be otherwise produced without departing from the invention.

What I claim is:—

1. In a corner-fastening for bedsteads, the combination with a corner-post, of a 115 hollow rectangular shell fastened thereto, an angle bar of the bed-bottom supporting frame capable of being reversibly extended into said shell, and a cam lever oscillatably mounted upon said shell for clamping said 120 angle bar to said shell, said cam lever having two oppositely disposed cam faces coacting with oppositely disposed portions of said shell.

2. In a corner-fastening for bedsteads, the 125 combination with a corner-post, of a hollow rectangular shell fastened thereto, an angle bar of the bed-bottom supporting frame capable of being reversibly extended into said shell, and a cam lever oscillatably mounted 130

upon said shell for clamping said angle bar to said shell in either position, said cam lever having two oppositely disposed cam faces, one of said faces exerting pressure directly upon the horizontal flange of said angle bar when extending uppermost and the other face upon the horizontal flange of said angle bar when extending lowermost.

3. A corner-fastening for bedsteads according to claim 2, comprising a lug on the inner face of said shell, and a side cam face on said lever coacting with said lug for binding the vertical flange of said angle bar against one of the walls of said shell in either position of said angle bar.

4. In a bed lock, the combination of a member having an opening therein, into which an angle iron frame member may be inserted, and an arm pivoted to said first member, having a handle portion and a head portion having an inclined surface, adapted to be swung into position to wedge an inserted frame member against an inner surface of said first member when said frame member is positioned with its horizontal

flange up, and another inclined surface adapted to engage the horizontal flange of said frame member, to wedge said frame member against an inner surface of said first member, when said frame member is positioned with its horizontal flange down.

5. In a bed lock, the combination of a member having an opening therein into which may be inserted an angle-iron frame member, and a hand lever pivoted to said first member below the opening, said lever having a handle and a head extending at an angle thereto, said head having a surface adapted to wedge the frame member against a wall of the opening when said member is positioned with its horizontal flange up, and another surface adapted to wedge the frame member against a wall of the opening when said member is positioned with its horizontal flange down.

Signed at New York, in the county of New York and State of New York, this 15th day of December, A. D. 1921.

MORRIS LOWY.
